UNITED STATES PATENT OFFICE.

WILLIAM W. WEIR, OF ALAMEDA, CALIFORNIA.

DESIGN FOR A FIREPLACE HEATER.

Application filed September 13, 1923. Serial No. 7,194. Term of patent 14 years.

To all whom it may concern:

Be it known that I, WILLIAM W. WEIR, a citizen of the United States, and a resident of Alameda, county of Alameda, State of California, have invented a new, original, and ornamental Design for a Fireplace Heater, of which the following is a specification, reference being had to the accompanying drawing, forming part thereof.

The figure is a front elevation of the fireplace heater illustrating my new design.

I claim:

The ornamental design for a fireplace heater substantially as shown.

WILLIAM W. WEIR.
